(57) CLAIM

The ornamental design for a bottle for storing and aging beverages, as shown and described.

DESCRIPTION

FIG. 1 is a perspective view of a bottle for storing and aging beverages according to the present invention;

FIG. 2 is a side view of a bottle for storing and aging beverages thereof;

FIG. 3 is another side view of a bottle for storing and aging beverages thereof;

FIG. 4 is another side view of a bottle for storing and aging beverages thereof;

FIG. 5 is another side view of a bottle for storing and aging beverages thereof;

FIG. 6 is a top view of a bottle for storing and aging beverages thereof; and,

FIG. 7 is a bottom view of a bottle for storing and aging beverages thereof.

The surface shading and contour lines in the drawings is a drawing convention to represent character and contour; it does not illustrate material, surface ornamentations, or surface decoration and forms no part of the claimed design.

1 Claim, 6 Drawing Sheets
